UNITED STATES PATENT OFFICE.

MAURICE ALLAND, OF ATLANTIC CITY, NEW JERSEY.

COMBINED COMB AND RAZOR.

Application filed August 23, 1927. Serial No. 214,843.

The object of the invention is to provide improvements in toilet articles, comprising combs and razors and more particularly in the suitable combination of two such articles, 5 so that they can be used either independently of, or in combination with, each other.

When men's hair has not been trimmed for several days, the ends generally show an irregularity or raggedness, but such a condition 10 is not corrected as a rule until the hair as a whole needs cutting, or retrimming. In the meantime, a man's appearance becomes less and less attractive, whereas with the present 15 device he is able himself to keep his hair in first class condition, so that it constantly appears to have been but newly cut and trimmed.

With women a similar condition has developed since the advent of bobbed hair, and each girl or lady frequently wishes that she 20 might be able to put her hair in first class shape, without having to visit a barber to have the entire head gone over. However, since a woman's hair is generally thicker than a man's, the comb for her use is preferably 25 provided as heretofore with longer teeth, providing a greater depth between them, while the means for supporting and operating the razor are the same.

Another object is to provide for the use of 30 the blade upon the outside of the comb, when for instance, trimming of the shorter hair of the neck is desired, while in this latter position the blade is also adapted for use for shaving the face and neck in the usual manner, and after such use to be sheathed within 35 and protected by the comb.

A further object is to provide an improved 40 method of making the present combination comb and razor, wherein the chamber within the former for retaining the latter is obtained by forming the comb first by flattening a tube about a suitable core or form, and then cutting the necessary teeth laterally in the collapsed tube.

45 Still another object is to provide a specially designed means for removably securing the blade to the outside of the comb, while it is desired to use it in this position, said means being efficient yet comprising no material ob- 50 struction to the free use of the device.

And still further details of construction are fully brought out in the following description, when read in conjunction with the accompanying drawings, in which Fig. 1 is 55 a perspective view of a hollow tube from

which the comb is formed; Fig. 2 is a similar view of the tube flattened upon a suitably shaped core; Fig. 3 is a horizontal section thru the same; Fig. 4 is a plan view of one embodiment of the invention and of a shape 60 most convenient for use by men; Fig. 5 is a section on the line 5—5 of Fig. 4; Fig. 6 is a section on the line 6—6 of Fig. 5; Fig. 7 is an enlarged fragmentary section on the line 7—7 of Fig. 4; and Fig. 8 is a plan view of a comb, 65 having a shape especially adapted for use by ladies, and also embodying the present invention.

Referring to the drawings, in the manufacture of the improved comb, a hollow tube 1 is flattened upon a core 2, (as shown in Fig. 2), which thereafter is withdrawn and the resulting "blank" slotted to form the usual teeth 3, which extend well into the body of the device and intersect the central recess 4, which is adapted to contain any suitable type of so-called "safety" razor blade 5, having oppositely directed cutting edges 6, and a pair of spaced apertures 7.

When the blade is positioned within the 80 comb, and the latter is drawn thru the hair in the usual manner, the edges of the latter come in contact with the outer layers of the hair in the spaces between the teeth, while the inner end of the blade bears against a 85 stop in the form of a pin 8, which is slidable in parallel slots 9 cut in the opposite sides of the comb, and is prevented from becoming disengaged from said slot by a head 10 upon one end, and an undercut head 11 upon 90 the outer end.

A fixed stud 12 is also secured to that side 95 of the comb from which protrudes the undercut head 11 of the pin 8, and is also provided with an undercut head 13, the recesses in said heads facing in the opposite directions. When the blade is within the recess 4, it may be shifted outwardly by manually engaging and moving the pin 8 laterally. After the said pin has reached its limit 100 of movement, the opposite end of the blade extends sufficiently beyond the end of the comb to be grasped and withdrawn completely therefrom.

Then, in order to secure said blade upon 105 the outside of the comb, they are associated in such manner that the heads 11 and 13 extend thru the corresponding apertures 7 in the blade, after which the pin is shifted in the reverse direction, so that those portions of 110

the blade adjacent to and upon the opposite sides of said apertures are secured beneath the undercut portions of said heads. In this position, the edges of the blade are exposed 5 for use either upon hair drawn thru the teeth of the comb, or directly upon the face where the protruding teeth of the comb serve only as a guard for the edges of the blade, to protect the latter against cutting the skin 10 of the user.

In the form of the device illustrated in Fig. 8, the construction of the right-hand end portion is as hereinbefore described, but the teeth 14 upon the lower side of the opposite, or left-hand, end are made longer, and from a solid piece of material set into the collapsed tube, so that this portion of the comb can be used satisfactorily in arranging the longer and thicker hair of women and 20 girls, as compared with the hair of the length usually worn by men.

Having thus described my invention, what I claim and desire to protect by Letters Patent of the United States is:—

25 1. A toilet article, comprising a hollow tubular comb, a razor blade positioned within said comb with its cutting edges exposed between the teeth of the comb, and a pin extending transversely thru said comb and 30 movable longitudinally of the comb, to eject said blade.

2. A toilet article, comprising a hollow tubular comb, a razor blade having a pair of apertures and positioned within said comb 35 with its cutting edges exposed between the teeth of the comb, to trim hair passing thru the comb, a stud having an undercut head

and fixed to the outer side of the comb, and a pin extending transversely thru said comb and having an undercut head projecting laterally beyond the said outer side of the comb, said pin being manually movable longitudinally of the comb to eject the blade, and also movable to secure the blade upon the exterior surface of the comb, after the heads of said stud and said pin have been inserted thru the apertures of the blade, to permit direct shaving with the blade, while the comb teeth operate as guards for the blade. 40 45

3. A toilet article, comprising a comb, one end portion of which is of hollow tubular construction, a razor blade positioned within said hollow portion with its cutting edges exposed between the teeth of the comb, the comb teeth upon one side being of uniform depth, the teeth upon the other side being of different depths to accommodate hair of differing thickness, a stud having an undercut head and fixed to the outer side of the comb, and a pin extending transversely thru said comb and having an undercut head projecting laterally beyond the said outer side of the comb, said pin being manually movable longitudinally of the comb to eject the blade, and also movable to secure the blade upon the exterior surface of the comb, after the heads of said stud and said pin have been inserted thru the apertures of the blade, to permit direct shaving with the blade, while the comb teeth operate as guards for the blade. 50 55 60 65 70

In testimony whereof I have affixed my signature.

MAURICE ALLAND.
